UNITED STATES PATENT OFFICE

105,165

DESIGN FOR A COMBINED COMB AND BRUSH

John Denman Dean, Tolworth, England

Application March 8, 1937, Serial No. 68,079

Term of patent 7 years

To all whom it may concern:

Be it known that I, John Denman Dean, a subject of the King of Great Britain and resident of Tolworth, in the county of Surrey, England, have invented a new, original, and ornamental Design for Combined Comb and Brush, of which the following is a specification, reference being had to the accompanying drawing, forming part thereof.

Figure 1 is a perspective view of a combined comb and brush embodying my new design,

Figure 2 is a perspective view of the combined comb and brush shown in Figure 1 with the bristles omitted, and

Figure 3 is a perspective view of the article shown in Figure 1 with the comb omitted.

I claim:

The ornamental design for a combined comb and brush as shown and described.

JOHN DENMAN DEAN.
